DESIGN FOR A GAME APPARATUS

Raymond T. Moloney, Chicago, Ill.

Application June 17, 1933. Serial No. 48,432

Term of patent 3½ years

To all whom it may concern:

Be it known that I, RAYMOND T. MOLONEY, a citizen of the United States, residing at Chicago, in the county of Cook and State of Illinois, have invented a new, original, and ornamental Design for a Game Apparatus, of which the following is a specification, reference being had to the accompanying sheet of drawing, forming part thereof.

The drawing shows in Figure 1 a plan view of my game apparatus design, and in Figure 2 a side view, partly in section, on a reduced scale.

I claim:

The ornamental design for a game apparatus, as shown.

RAYMOND T. MOLONEY.
